(57) **CLAIM**

We claim the ornamental design for a “laser light projector,” as shown and described.

DESCRIPTION

FIG. 1 is a perspective view of the laser light projector; and, FIG. 2 is a front view of the laser light projector of FIG. 1; FIG. 3 is a back view of the laser light projector of FIG. 1; FIG. 4 is a right side view of the laser light projector of FIG. 1;

FIG. 5 is a left side view of the laser light projector of FIG. 1;

FIG. 6 is a top view of the laser light projector of FIG. 1; FIG. 7 is a bottom view of the laser light projector of FIG. 1;

FIG. 8 is an environmental view of the laser light projector of FIG. 1; and,

FIG. 9 is another environmental view of the laser light projector of FIG. 1.

Broken lines illustrate environmental features and form no part of the claimed design.

The nature and intended use of the article in which the design is embodied is the projection of light.
